DESIGN FOR AN ELECTRIC TIMER

Alexander I. Newman, Chicago, Ill., assignor to
Precision Scientific Co., Chicago, Ill., a corpora-
tion of Illinois

Application July 22, 1940, Serial No. 93,836

Term of patent 7 years

To all whom it may concern:

Be it known that I, Alexander I. Newman, a citizen of the United States, residing at Chicago, in the county of Cook and State of Illinois, have invented a new, original, and ornamental Design for an Electric Timer, of which the following is a specification, reference being had to the accompanying drawing, forming a part thereof.

Figure 1 is a perspective view of an electric timer embodying my new design;

Figure 2 is a top view of the same; and
Figure 3 is a front elevational view of the same.

I claim:

The ornamental design for an electric timer, substantially as shown.

ALEXANDER I. NEWMAN.
